UNITED STATES PATENT OFFICE

2,509,809

COMBINATION MULTIPLE SWITCH UNIT
AND ORNAMENTBerton E. Cook, Chicago, Ill., assignor to Milton
M. Blumenthal, Chicago, Ill.

Application June 11, 1947, Serial No. 753,965

13 Claims. (Cl. 315—186)

1

This invention relates generally to electrical switch units and particularly to portable switch units for domestic, industrial and decorative illuminating purposes. More particularly, the invention is directed to a novel portable switch unit built into an unique and ornamental receptacle containing a plurality of plug outlets for electrical appliances and the like and especially for lighting sets, particularly of the class adapted for attachment to Christmas trees and the like, for decorative illuminating purposes.

The decorative illumination of Christmas trees has in recent years become so complex that the ordinary householder often does not have the knowledge or ability to assemble and connect the necessary equipment required therefor. Thus, he must hire an electrician or utilize a simpler but less decorative illuminating system. However, oftentimes he attempts to "muddle through" himself; the result being a dangerous electrical system which may and often does cause conflagration and accidents. On the other hand, despite the fact that an expert electrician may be retained to assemble the system, temporary connections, switches and the like must be used so that a cumbersome, unsightly and even dangerous illumination system cannot be avoided.

In recent years, several electrical fittings and attachments have been introduced for the purpose of simplifying the systems. However, none of these have proven very successful either in simplifying the systems or in minimizing the danger. Furthermore, they are obsolete in so far as modern electrical systems are concerned.

It is, therefore, a primary object of this invention to provide a device of the character described, which will overcome all of the disadvantages set forth above.

It is a further object of this invention to eliminate the numerous unsightly and dangerous attachments and the like heretofore utilized in the electrical systems to which this patent pertains, and to substitute therefor a combination unit which will serve as an ornament rather than a disfigurement. An object pursuant thereto is to provide a unit receptacle of a suitable shape, material and design that it may be used as a tree ornament.

A further related object is to provide said ornament with illuminating means.

A further object of this invention is to afford a combination switch unit having means for readily positioning and securing said unit to an object such as a Christmas tree branch.

Another object of this invention is to provide a

2

single unit to which the leads of all the tree lamp sets may be electrically connected.

Yet another object is to afford a combination switch unit having a single lead wire and male plug so that the entire system may be electrically connected to a single house current outlet.

Yet a further object is to provide a single unit which may independently control the electrical system. An object relating thereto is to provide switching means in the unit by which the system may be controlled. It will be apparent that such independent control means eliminates the necessity for relying on control thereof by a house switch or floor or wall outlet connection.

15 Still another object is to eliminate the danger of conflagration caused by short circuit breaks and the like. An object pursuant thereto is to provide a fuse in the switch circuit.

A related object is to afford a fused switch unit 20 which will eliminate the blowing of house fuses by short circuits in the tree illuminating system.

A further object is to provide a combination switch unit having a diversity of control means such as means for intermittent or flashing tree 25 illumination.

A related object is to provide means for selectively controlling such intermittent and continuous lighting.

Yet another object is to provide a portable unit 30 tary table receptacle into which a plurality of electrical appliances and the like may be plugged and centrally controlled.

Another object is to provide a table receptacle having means for supporting the receptacle in 35 a position permitting ready access to the plug outlets.

Still a further object is to provide a combination switch unit having illuminating means therein which may be dimmed to adapt said unit for use 40 as a bed lamp and the like.

Another object is to afford a combination electrical switch unit and ornament of sturdy safe construction, yet simple and inexpensive.

With the foregoing and other objects in view 45 which will appear as the description proceeds, the invention consists of certain novel features of construction, arrangement and a combination of parts hereinafter fully described, illustrated in the accompanying drawings, and particularly

50 pointed out in the appended claims, it being understood that various changes in the form, proportion, size and minor details of the structure may be made without departing from the spirit or sacrificing any of the advantages of the invention.

55

For the purpose of facilitating an understanding of my invention, I have illustrated in the accompanying drawings a preferred embodiment thereof, from an inspection of which, when considered in connection with the following description, my invention, its mode of construction, assembly and operation, and many of its advantages should be readily understood and appreciated.

Referring to the drawings in which the same characters of reference are employed to indicate corresponding or similar parts throughout several figures of the drawings:

Figure 1 is a front elevational view of the invention with the cover of the receptacle removed to show the inner parts.

Figure 2 is a perspective view of a switch unit embodying my invention showing the same in operational position on the branch of a Christmas tree.

Figure 3 is a perspective view showing the back of the unit as supported in plug-accessible-position.

Figure 4 is a schematic wiring diagram showing the electrical circuits and parts of the switch unit comprising this invention.

Referring more particularly to the drawings, the reference character 10 denotes a switch unit embodying my invention comprising a receptacle designated generally by the reference numeral 11 and having a hook 12 affixed at the top thereof.

The receptacle 11 may be formed of a separable housing comprising a cup shaped back member 13 and a front cover member 14. Cover 14 may be affixed to back member 13 by means of screws such as 15 threaded through the cover and into retaining lugs as 16, which protrude inwardly from the walls of said cup member 13. Air holes 14' may be provided in cover 14 for cooling the receptacle cavity.

Although the above described receptacle structure is revealed in the drawings, I do not wish to be limited thereto since any conventional separable housing may be utilized without departing from the spirit and scope of my invention. Thus, a separable receptacle housing, both parts of which are cup shaped with one slightly smaller than the other to permit telescoping of one within the other, and having a conventional self-locking snap fastener formed therein, may be utilized in this invention. Furthermore, although the drawings show the receptacle in the ornamental shape of a bell, it should be evident that any appropriate ornamental shape may be used. Thus a star, cross, figure and the like shaped receptacle may be utilized without departing from the spirit and scope of this invention.

Within the housing 13 is positioned and formed or secured therein the various electrical parts and wires which comprise the electrical circuits of the switch. Thus, a lead cable 17 having a male plug 18 at one end may have its other end 19 inserted into the receptacle 11. One of the wires 20 of this cable is bound at its other end to a binding post 21 of a fuse 22 which is connected in series in the circuit. This fuse 22 is mounted in a retainer 23 which may be formed in or secured to the back of cup member 13.

The fused lead is completed by a wire 24 which is electrically connected at one end to an opposite fuse terminal post 25 and at the other end to a bus bar terminal 26. Terminal 26 is affixed to a bus bar 27 which together with its parallel bus bar 28 form a parallel electrical connection between the multiple protected plug outlets as 29, formed in or secured to the back wall of the

housing 13. The plug outlets 29 and their bus bar connectors 27 and 28 may, if so desired, be constructed as a conventional single unit 30 which may then be assembled in the unit. However, the outlets may be formed directly in the receptacle housing 13 if desired, for convenience of construction.

The plug outlets 29 are adapted to receive therein the male plugs of the leads of any electrical appliances and the like or the leads as 31 of tree light sets such as 32. The wires as 33 and 34 are plugged directly into the unit and the lamps as 35 are connected either across the wires as 33 and 34 in parallel, as shown in Fig. 4, or in series as desired.

An electric lamp 36 is connected in parallel in said circuit by means of wires 37 and 38 the free ends of which are brought into electrical contact with bus bars 27 and 28 as at binding posts 39 and 40. This lamp serves to illuminate the receptacle so as to afford an illuminated ornament. Lamp 36 may be positioned and secured within the receptacle by any conventional method. However, I prefer to use a mounting such as 41 which may be formed in or secured to the back wall of housing member 13.

The constant light circuit is completed by a lead 42 which is connected at one end to the bus bar 28 by means of a binding post 43 and at the other end to a conventional switch 44 which controls the opening and closing of the constant light circuit.

Although constant illumination is the usual and ordinary lighting most often used, oftentimes it is desired to vary this as by creating an intermittent lighting effect. Novel means for affording such an effect are incorporated in this invention. Thus, a thermal flasher 45, the details of construction of which will be later described, is connected into an alternate circuit by means of a wire 46 which may be bound to the binding post 40 at its other end. This circuit is completed by a wire 47 which connects the flasher 45 to a flasher switch 48 which is shown in Fig. 1 as being similar to the constant light switch 44.

To complete the circuit a wire 49 having one end 50 connected to or comprising one of the wires of line cable 17, is connected at its other end 51 to the flasher switch 48. Wire 52 is spliced at one end with wire 50 as at 53 and at the other end is connected to the constant light switch 44. Thus, the circuit may be completed selectively by closing either constant light switch 44 or flasher switch 48 depending upon the type of illumination desired.

The thermal flasher unit 45 which is used to create intermittent illumination is comprised of a bi-metal bar 55 fixed at one end as at 56 and having a terminal contact 57 at the other end. Wire 47 is coiled around the bar 55 as at 58 so that it may generate heat to cause the bar to curl upward at its free end until contact is made with a contact terminal 59. Terminal 59 is affixed to the end of an adjusting screw 60 which is threaded through an opening near the end of a terminal bar 61. Terminal bar 61 is in turn electrically joined to line 46 in the circuit. The bi-metal bar 55 is also connected to line 47 by wire 62 and the free end of coil 47 is connected to terminal 63 of line 46.

In operation, upon the closing of switch 48 the current passes through the coil 58 until sufficient heat has been generated thereby to cause the bi-metal bar to curl upward until the circuit between terminals 57 and 59 is completed.

Since the bar resistance is less than that of the coil the current then flows through this circuit; but only momentarily, because the bi-metal bar upon cooling, in the absence of heat from the coil, soon breaks the contact between terminal 57 and 59. Upon the breaking of this circuit the current again flows through the coil 58 and the cycle is repeated.

In the event that the unit is to be used as a table receptacle, then the outlets 29 must be made accessible so that appliance terminal plugs may be inserted therein. This may be accomplished by providing an arm 65 hinged at one end as at 66 so that the arm may be swung outwardly to position the receptacle on its side. Again any convenient supporting structure may be used in combination with my invention without departing from the spirit and scope of this invention.

It is believed that my invention, its mode of construction and assembly, and many of its advantages should be readily understood from the foregoing without further description, and it should also be manifest that while preferred embodiment of the invention has been shown and described for illustrative purposes, the structural details are nevertheless capable of wide variation within the purview of my invention as defined in the appended claims.

What I claim and desire to secure by Letters Patent of the United States is:

1. A device adopted to afford a plurality of protected electrical outlets comprising a housing, bus means connected with said outlets, means for connecting said bus means to a power line, said last mentioned means including a permanently connected fused lead, and a pair of parallel leads each capable of being independently connected in said circuit, one of said leads having an automatic flashing device electrically connected therein.

2. A device adopted to afford a plurality of protected electrical outlets comprising an ornamental plastic housing, means for illuminating said housing, a hook formed at the top of said housing for suspending the same from a standard or the like, bus means connected with said outlets and said illuminating means, said housing having means for connecting the same with a power line, said last mentioned means including a permanently connected fused lead and a pair of parallel leads, an automatic flashing device connected in one of said leads, and means for selectively connecting said leads in said circuit.

3. A device adopted to afford a plurality of protected electrical outlets comprising an ornamental plastic housing, means for illuminating said housing, a hook formed at the top of said housing for suspending the same from a standard or the like, bus means connected with said outlets and said illuminating means, said housing having means for connecting the same with a power line, said last mentioned means including a permanently connected fused lead and a pair of parallel leads, an automatic flashing device connected in one of said leads, and means for selectively connecting said leads in said circuit, said last mentioned means comprising a pair of switches connected to said leads and adopted to independently connect each of said leads in said circuit.

4. In combination a tree ornament having means positioned internally thereof for illuminating said ornament, a plurality of electrical

outlets, power connecting means for said ornament, and means for connecting said outlets to said power connection for constant and intermittent power flow, said intermittent power-flow-controlling-means comprising an automatic circuit-making-and-breaking device.

5. In combination a tree ornament having means positioned internally thereof for illuminating said ornament, a plurality of electrical outlets, power connecting means for said ornament, means for connecting said outlets to said power connection for constant and intermittent power flow, and a fuse interposed between said outlets and said power connecting means, said intermittent power-flow-controlling-means comprising an automatic circuit-making-and-breaking device.

6. In combination a tree ornament having means positioned internally thereof for illuminating said ornament, a plurality of electrical outlets, power connecting means for said ornament, means for connecting said outlets to said power connection for constant and intermittent power flow, a fuse interposed between said outlets and said power connecting means, and switching means for selectively controlling said constant and intermittent power flow, said intermittent power-flow-controlling-means comprising an automatic circuit-making-and-breaking device.

7. In a multiple switch unit affording a plurality of electrical outlets, a circuit for connecting and controlling said outlets to a power source, said circuit comprising a fused lead, means for connecting said lead to said electrical outlets, an auxiliary circuit connected to said main circuit and comprising a pair of parallel leads, each capable of being independently connected in said circuit and one of said leads having an automatic flashing device connected therein.

8. In a multiple switch unit affording a plurality of electrical outlets, a circuit for connecting and controlling said outlets to a power source, said circuit comprising a fused lead, means for connecting said lead to said electrical outlets, an auxiliary circuit connected to said main circuit and comprising a pair of parallel leads, a pair of switching means for completing the circuits through said leads, and circuit interrupting means in one of said leads, one of said switching means controlling said circuit interrupting means.

9. In a device of the character described, a plurality of protected electrical outlets, means for connecting said outlets to a power line, a plurality of means for controlling the electrical connection between said power line and said outlets, at least one of said controlling means comprising an automatic circuit-making-and-breaking device.

10. In a multiple switch unit affording a plurality of electrical outlets, a circuit for connecting and controlling said outlets to a power source, an auxiliary circuit connected to said main circuit and comprising a pair of parallel leads, each capable of being independently connected in said circuit, and one of said leads having an automatic flashing device connected therein.

11. In a multiple switch unit affording a plurality of electrical outlets, a circuit for connecting and controlling said outlets to a power source, an auxiliary circuit connected to said main circuit and comprising a pair of parallel leads, circuit interrupting means in one of said leads, and

switching means for completing the circuits through said leads.

12. In a device of the character described, a protected electrical outlet, means for connecting said outlet to a power line, means for controlling the electrical connection between said power line and said outlet, at least one of said controlling means comprising an automatic circuit-making-and-breaking device.

13. In a device of the character described, a protected electrical outlet, means for connecting said outlet to a power line, means for controlling the electrical connection between said power line and said outlets including an automatic circuit-making-and-breaking device.
